UNITED STATES PATENT OFFICE.

FRENCH S. EVANS, OF WASHINGTON, DISTRICT OF COLUMBIA.

DESIGN FOR A CANE-HANDLE.

SPECIFICATION forming part of Design No. 21,784, dated August 23, 1892.

Application filed July 25, 1892. Serial No. 441,208. Term of patent 3½ years.

To all whom it may concern:

Be it known that I, FRENCH S. EVANS, a citizen of the United States, residing at Washington, in the District of Columbia, have invented and produced a new and original Design for Cane Heads or Handles, of which the following is a specification, reference being had to the accompanying drawings, showing the parts thereof.

10 Figure 1 is a plan of the hand end of a cane, showing one part of my design. Fig. 2 is a side elevation of the hand end of a cane, showing another part of my complete design; and Fig. 3 is also a side elevation of the side

15 opposite that shown in Fig. 2.

The leading features of my design for a cane-head consist, first, in a convex medallion representing General U. S. Grant; second,

in a shield on the side of the handle embracing a representation of a Grand-Army badge, 20 and, thirdly, in the scarf-like scroll on the opposite side of the handle.

A is the main part or body of the cane.

B is the cane head or top, having thereon a figure C, representing a medallion portrait of 25 General U. S. Grant.

D represents a Grand-Army badge on the circular handle, and E indicates a scarf-like scroll on the opposite side of the handle.

What I claim is—

30 The design for a cane-handle, substantially as herein shown and described.

FRENCH S. EVANS.
